UNITED STATES PATENT OFFICE.

EDWARD HILSON, OF NEW YORK, N. Y.

DESIGN FOR A BLANK FOR CIGARETTE-BOX CAPS.

SPECIFICATION forming part of Design No. 35,127, dated September 17, 1901.

Application filed January 29, 1900. Serial No. 3,248. Term of patent 3½ years.

To all whom it may concern:

Be it known that I, EDWARD HILSON, a citizen of the United States, residing at New York city, borough of Manhattan, in the county of New York and State of New York, have invented and produced a new and original Design for Blanks for Cigarette-Box Caps; and I do hereby declare the following to be a full, clear, and exact description of the invention, such as will enable others skilled in the art to which it appertains to make and use the same.

The drawing shows a plan of the blanks in which the special features of my design are clearly displayed.

15 The leading features of my design consist of the parts A A', B B', D D', E, F, and G, all of which are of a general rectangular form; the horizontal broken lines e f g h; the vertical broken lines a b c j, and the

solid line i. The bottom edge k of the part 20 A has a concave curved form, the parts D D' have their upper and opposite corners rounded, and the part F has both of its upper corners rounded.

It is apparent that this design is also applicable to cigar-boxes and similar articles.

Having described my invention, what I claim as new, and desire to secure by Letters Patent, is—

The design for a blank for a cigarette-box 30 cap as shown and described.

In testimony that I claim the invention above set forth I do affix my signature in presence of two witnesses.

EDWARD HILSON.
